CENTERING DEVICE

Charlton A. Alexander, St. Louis, Mo., assignor
to Joseph Robinson, Santa Monica, Calif.

Application March 7, 1921, Serial No. 450,468
Renewed August 26, 1932

10 Claims. (Cl. 285—58)

This invention relates to a centering head and associated parts forming together a device for supporting and centering the heavy head casting used to automatically couple the three separate fluid conduits found on all passenger railway cars, and the invention has for its object the simplification of such centering head and associated parts so that all advantages of present equipment will be retained while reducing the number 10 of parts and the difficulty of assembling the rod and stem on the head. A very successful type of supporting mechanism for fluid coupler heads is shown in application No. 397,814, filed July 21, 1920, by Charlton A. Alexander and Leonidas D. 15 Woodruff, and the present application is in one sense merely a simplification of the centering head shown in that application.

The principal features of the present structure are the provision of an upstanding pin integral 20 with the lower shelf of the centering head; the provision of a stem having a single slot in its lower sliding surface and the provision of slight guiding ribs leading to the guiding brackets on the side of the stem.

25 Other objects of the invention will be apparent from the following description, and are specifically covered by the claims, such other improvements consisting in an appreciable saving of material over older devices, and a general simplification of the parts.

In the drawings,—

Figure 1 is a longitudinal vertical section through the device.

35 Fig. 2 is a plan view of the stem and showing the centering head in section.

Fig. 3 is a vertical sectional view taken on the line 3—3 of Figure 1 and showing the centering head in front elevation.

40 The centering head 10 is supported from the circular support 11 of the bracket 12 in the usual manner and as fully explained in the previously mentioned application. At its front end the disk 14 of the centering head has an upwardly and 45 inwardly extending lip 15 which overlies the front portion of the circular support 11 and provides the means for holding these in operative position, such position of the parts being maintained by the action of gravity on the fluid coupler head (not 50 shown) so as to hold the rear bearing surface 16 against the lower rear edge of the support. The turntable pin 17 may be held in position by any desired means as, for example, by an inwardly projecting retaining lug 18 and a cotter 55 pin 19 as shown, this construction being equally

as efficient and much cheaper to manufacture than the usual headed pin which is a casting.

The centering head is formed with a central opening 20 through which passes the stem 21 which carries the fluid coupler head, connection 60 being made by a king bolt which passes through the aligned holes 22 and 23 of the shank 24 of the stem. The body of the hollow stem is generally rectangular in shape but has a slot in the lower or bearing face of the stem. This slot is 65 formed in two portions, a rear portion 26 and a wider front portion 27, the latter extending from the collar 28 to a point about half-way to the transverse abutment 29, while the narrower portion of the slot which is connected to the wider 70 portion by the converging walls 26' is of a length corresponding to the length of the shelf 30 which forms the support for the stem 21.

The transverse abutment plate 29 is generally 75 rectangular in shape as best shown in Fig. 3 and extends slightly to either side of the rear portion of the centering head forming wings 32 which engage a shoulder 54 on either side of the centering head to support the weight of the fluid coupling head. This plate 29 is also provided 80 with slightly curved enlargements 33 and 34 to receive the larger end 35 of the spiral spring 36 which is held in place by a centrally perforated circular boss 37 at the center of the rear abutment plate and integral therewith.

At its front end, the shelf 30 carries a preferably integral pin 40 generally cylindrical but having a curved groove 41 to receive the eye 42 of the rod 43 which forms the connecting link between the centering head and the stem, and 90 holds in place, by means of an adjustable nut 43', the smaller end of the spring 36, which consequently resiliently holds the abutment plate of the stem against the flat rear wall of the centering head 10.

95 The lower wall 45 of the stem is normally in engagement with the upper surface of the shelf 31 while in uncoupled position, but when coupled the relatively higher surface 46 of the stem rests upon the shelf. The stem during the act 100 of coupling slides gently down the rear inclined surface 47, thus bringing the pin 40 within the wider portion 27 of the slot.

On either side of the vertical center line of the stem the abutment plate is strengthened by 105 means of stiffening and guiding ribs 50 either three in number or but two as illustrated. In case only two are provided they are preferably flush with the upper and lower flat surfaces of the stem and are sloped to agree with the out- 110

ward flare of the sides of the centering head. Sloping surfaces 51 are also provided on either side of the main body of the stem at top and bottom and are joined to the larger ribs 50 by the relatively small extension 52, the combined action of the surfaces 51 and 50 being to guide the stem gently in place in the centering head.

In operation the parts of the device before coupling are as shown in Fig. 1 with the abutment plate in contact with the rear wall of the centering head 10. The spring 36 does not in any way carry the weight of the fluid coupler head which as stated is rigidly attached to the stem 21, the latter being held in horizontal position by the pressure of the spring 36. The action of gravity is resisted by the locking engagement which exists between the bottom surface of the stem which rests upon the flat shelf of the centering head, together with the engagement of the upper corners and the small projections 53 of the rear abutment plate with the shoulders 54 of the centering head. It will be noted that in the position shown, these two contacts support the entire weight of the coupling head and entirely prevent downward movement of the front portion of the shank unless the stem itself be moved rearwardly.

Although the parts, as previously stated, are locked in position as long as the stem is at the forward end of its travel, the stem is perfectly free to move either backward or upward or to either side. Movement directly rearward merely frees the engagement between the upper corners of the rear abutment and the shoulder 54 and if the movement is more than a slight one it also lowers the horizontal central line of the stem because of the engagement of the inclined portions of the stem and centering head respectively. Still further backward movement of the stem brings the forward bearing surface 46 over the flat shelf of the centering head and also brings the wide portion 27 of the slot abreast of the pin, at which time the coupling head may move freely in any direction including downward. Its weight, together with the weight of the stem, rests at all times on the shelf which not only avoids the necessity of providing a powerful weight-supporting spring, but also avoids too sudden or "snappy" movement of the parts. The spring 36 should, however, be made sufficiently strong to restore the parts to normal uncoupled position at a fairly rapid rate, for if the return action is made too slow the coupling head is liable to cant and will not engage properly with the centering head.

The stem is assembled in the centering head by raising the forward shank portion until it just clears the depending lug 18 and lowering the rear of the stem which readily permits the pin 40 to enter the large portion 46 of the slot. The rod 43 is purposely made sufficiently long to accommodate the nut 43' when the spring 36 is in entirely extended condition. The eye 42 takes a universal movement at one point on the upright pin or hook 40 and the distance between the top of the pin and the inner face of the top surface of the stem in uncoupled position is made less than the diameter of the rod 43 so that when the stem is in coupled position the top of the pin 40 will just clear the upper wall of the stem.

What I claim is:

1. A stem for automatic coupler heads, consisting of a hollow member provided with a slot in its lower portion, a transverse abutment at the rear of said member and guiding brackets ex-

tending from said transverse abutment to the main body of the member.

2. A stem for automatic train fluid coupler heads, consisting of a hollow member having a slot in its lower portion, a transverse abutment at the rear of said stem and extending beyond its margin at either side, a plurality of guiding brackets extending from the extending portions of said abutment and the body of said member and guiding ribs leading to said guiding brackets. 80

3. A stem for automatic fluid coupler heads, consisting of a hollow member having a lower portion, forming a bearing surface, said portion being provided with a slot, a transverse abutment at the rear of said stem and extending laterally thereof at either side and a plurality of guiding brackets connecting said stem and said abutment. 90

4. A stem for automatic fluid coupler heads, consisting of a hollow member having a slot in its lower portion, said slot being restricted in width at its rear end, a transverse abutment member at the rear of said stem extending laterally on either side thereof, and a plurality of guiding ribs connecting said stem with said abutment. 95

5. A stem for automatic fluid couplers, consisting of a hollow member having a slot in its lower portion, said slot being restricted in width at its rear end, the sides thereof being parallel 105 in such restricted portion, a transverse abutment member at the rear of said slot, said stem being deeper at its rear end than at its front end.

6. A stem for automatic fluid coupler heads, consisting of a hollow member, an abutment, a shank, said stem between said shank and said abutment having a lower bearing face in two planes connected by a sloping portion. 110

7. A stem for automatic fluid coupler heads, consisting of an abutment, a shank and a generally cylindrical body open at its lower side connecting said abutment and shank and a centrally perforated member closing the rear of said stem beyond said abutment. 115

8. In combination, a support having an opening therein bounded on the bottom by a horizontal shelf, an inclined portion leading to said shelf, a pin rising from and integral with said shelf, a slotted stem resting on said shelf with said pin extending within the slot, a plane front 120 bottom bearing surface on said stem, a plane rear bottom bearing surface farther from the axis of said stem than said front surface and an intermediate sloping bearing surface connecting said plane surfaces and cooperating with 125 said inclined portion to raise said stem when the latter is moved forwardly in said opening.

9. Means for supporting an automatic connector head for universal movement relative to a car comprising, in combination, a member rotatably supported from the car and arranged to rotate on a substantially vertical axis, said member having an opening therein, a head supporting stem extending in front of said member rearwardly through said opening, and yieldable 135 means for pressing said stem forwardly in said opening, said stem being provided with a longitudinal slot, a pin projecting from said member into said slot, a tie rod engaging said pin and extending rearwardly from said stem and said member, said yieldable means comprising a spring carried by said tie rod and engaging said stem. 140

10. Means for supporting an automatic connector head for universal movement relative to a car comprising, in combination, a member ro- 150

tatably supported from the car and arranged to rotate on a substantially vertical axis, said member having an opening therein, a head supporting stem extending in front of said member rearwardly through said opening, and yieldable means for pressing said stem forwardly in said opening, said member being provided with an integral pin extending upwardly from the bot-

tom of said opening, said stem having a longitudinal slot through which said pin extends, a tie rod hooked over said pin and extending rearwardly of said stem and member, said yieldable means comprising a spring carried by said tie rod 80 and engaging said stem.
